No. 744,315.

PATENTED NOV. 17, 1903.

F. A. ECKER.

PLATE RACK.

APPLICATION FILED JUNE 27, 1903.

NO MODEL.

UNITED STATES PATENT OFFICE.

FRANK A. ECKER, OF MIDDLETOWN, CONNECTICUT.

PLATE-RACK.

SPECIFICATION forming part of Letters Patent No. 744,315, dated November 17, 1903.

Application filed June 27, 1903. Serial No. 163,412. (No model.)

To all whom it may concern:

Be it known that I, FRANK A. ECKER, a citizen of the United States, residing at Middletown, in the county of Middlesex and State of Connecticut, have invented a new and useful 5 Plate-Rack, of which the following is a specification.

My invention is an improvement in plate-racks, the object of my invention being to 10 provide a rack of this description that will readily fold upon itself and can be locked in such folded position when not in use.

My invention consists in the novel features 15 of construction and combination of parts hereinafter described, particularly pointed out in the claims, and shown in the accompanying drawings, in which—

Figure 1 is a view of my rack complete in 20 position for use. Fig. 2 is a perspective view of the rack partly folded. Fig. 3 is a similar view showing the rack entirely folded. Fig. 4 is a detail view showing the manner of hinging the rear and bottom frames. Fig. 5 is a detail view showing the means for locking 25 the side and front frames together. In Figs. 2 and 3 the wire network is removed to more clearly illustrate the construction of the frame.

In constructing my rack I employ a rectangular 30 vertical rear frame A, braced by a horizontal cross-piece A'. The frame A is composed of a single piece of wire and is bent to form eyes A², through which screws may be passed to secure it to a baseboard or wall. The upper horizontal member has an eye A³, formed 35 intermediate its ends.

The bottom frame B is substantially rectangular in shape and is formed of one piece 40 of wire. This wire is bent to form loops or eyes B', projecting upward when the bottom is at right angles to the vertical frame above the plane of the bottom. A plurality of these eyes B' are formed on each side and end of the bottom frame B. The frames A and B are hinged together by the lower member of 45 the frame A passing through the eyes B', formed on the rear side of the frame B.

The end members C are simple rectangular 50 wire frames approximately equal in length to the width of the bottom frame, and a side member of each of the frames C engages the eyes B', formed on one of the end members

of the frame B. These side members are formed with a loop C' in what forms the upper front corners of the side frames when the 55 rack is unfolded. An eye C² is also formed on each side frame adjacent the loop C', and a hook member C³, pivoted to the eye C², is adapted to engage the loop C'.

The front member D is a one-piece wire 60 frame hinged to the forward side of the bottom frame by engaging a portion of the eyes B', as are the side and rear members. A loop D' is formed in the upper corners of the frame D, and when the frames D and C are 65 lifted into vertical position the loops D' project over the loops C', and the hooks C³ engaging the two loops lock the side and front frames in upright position.

A brace or chain formed of a plurality of 70 links E connects the rear frame and each side frame. A hook D², carried by the front frame D, engages the eye A³ when the parts are folded. By disengaging the hooks C³ from the loops C' D' the sides C will fold on the 75 frame B and the frames B and D on the frame A. A wire network F is carried by each frame, as shown in Fig. 1.

Having thus fully described my invention, 80 what I claim as new, and desire to secure by Letters Patent, is—

1. A device of the kind described comprising a rear vertical frame, a bottom frame hinged to the vertical frame, side frames hinged to the ends of the bottom frame, an 85 end frame hinged to the front side of the bottom frame, means for locking the side and front frames together, and a plurality of pivoted links connecting the upper portion of the rear frame with the forward portion of 90 the side frames.

2. A device of the kind described comprising a rear, rectangular frame, a horizontal bottom frame hinged to the lower edge of the rear frame, hinged side and front frames, a 95 chain of pivoted links connecting each side frame with the rear frame, the side frames folding on the bottom frame, the bottom, side and front frames folding on the rear frame a hook carried by the front frame and adapted 100 to engage the upper edge of the rear frame, and means for locking the front frame in a position at right angles to the side frames.

3. A device of the kind described compris-

ing a rear vertical frame, a swinging hinged bottom frame folding on the rear frame, side frames hinged to and folding on the bottom frame, a front frame hinged to the bottom frame and folding with it upon the rear frame, loops carried at a corner of each side frame, loops carried at the upper corners of the front frame and registering with the loops of the side frames, hook members pivoted to the

side frames and engaging loops of the side and front frames, an eye carried by the upper portion of the rear frame, and a hook carried by the front frame and adapted to engage the eye on the rear frame.

FRANK A. ECKER.
